(57) **CLAIM**

The ornamental design for a laser sight, as shown and described.

DESCRIPTION

FIG. 1 is a front view of embodiment 1 showing a laser sight of the new design;

FIG. 2 is a back view of embodiment 1;

FIG. 3 is a left view of embodiment 1;

FIG. 4 is a right view of embodiment 1;

FIG. 5 is a top view of embodiment 1;

FIG. 6 is a bottom view of embodiment 1;

FIG. 7 is a perspective view of embodiment 1;

FIG. 8 is another perspective view of embodiment 1;

FIG. 9 is yet another perspective view of embodiment 1;

FIG. 10 is a front view of embodiment 2 showing a laser sight of the new design;

FIG. 11 is a back view of embodiment 2;

FIG. 12 is a left view of embodiment 2;

FIG. 13 is a right view of embodiment 2;

FIG. 14 is a top view of embodiment 2;

FIG. 15 is a bottom view of embodiment 2;

FIG. 16 is a perspective view of embodiment 2;

FIG. 17 is another perspective view of embodiment 2; and,

FIG. 18 is yet another perspective view of embodiment 2.
